UNITED STATES PATENT OFFICE.

MICHAEL SWORASKI, OF PHILADELPHIA, PENNSYLVANIA.

AUTOMATIC TRAIN CONTROL.

Application filed September 27, 1926. Serial No. 137,945.

The principal object of the present invention is to provide a simple, reliable and efficient automatic train control which shall eliminate the personal equation in a satisfactory and safe manner. Another object of the invention is to cause a caution signal to cut off power and permit an engine to run or drift past the signal, and, if the latter is clear, to permit the engineer to again put on power, but if not clear, to put the brakes on automatically to a dead stop so that to start again the engineer must open up both power and brake valves.

The invention will be claimed at the end hereof but will be first described in connection with the embodiment of it chosen for illustration in the accompanying drawings forming part hereof and in which

Figure 1 is a diagrammatic view illustrating features of the invention and showing a signal interposed between two electromagnetic track trips.

Fig. 2 is a side view, partly in section of the upper part of the structure shown in Figure 1, and

Fig. 3 is a diagrammatic and schematic view partly in section illustrative of locomotive equipment.

In the drawings 1 and 2 are spaced electromagnetic strips arranged along the line of way, for example, between the rails 3 upon which the steam or electrically propelled locomotive or vehicle travels. As shown these electromagnetic trips are duplicates and a description of one is sufficient. 4 is an open top housing provided with a hinged or movable lid 5 of generally wedge shaped outside contour. The lid 5 is normally in the position shown at the left in Fig. 1, that is, closed or retracted. 6 is a solenoid interposed between the housing and lid and adapted when energized to open or project the lid. 7 is a signal interposed between the trips and having caution and stop provisions. The form of the signal is not material but as shown it comprises a semapore arm 8 having clear and caution and stop indicating means represented by 9, 10 and 11, which may be taken to be different colored lights when exhibited at night. It is immaterial by what means the signal is operated. There are circuit connections between the trips and the signal whereby at caution position the trip 1 on the oncoming side is set or pro-

jected and at stop position both trips are set or projected. Assuming the train or locomotive to be controlled by moving from right to left in Fig. 1, the trip 1 is set and the signal is in caution position. When the signal is turned counter-clockwise to stop position, both of the trips 1 and 2 are set or projected, and when the signal is turned clockwise to clear position, both the trips 1 and 2 are retracted. The signal is equipped with a contact actuator 12 which cooperates with spring opened circuit closures 13 and 14, that cooperate with a contact 15 connected by conductor 16 to one side of a source of current, and the circuit closer 13 cooperates with another contact 17, and the circuit closer 14 cooperates with two other contacts 18 and 19. The contact 17 is connected by conductor 20 to contact 18, and then by conductor 21 to the coil of the solenoid 6 of the trip 1. The solenoids of both the trips 1 and 2 are connected by conductors 22 and 23 to the source. The contact 19 is connected by conductor 24 through the solenoid of the trip 2.

Referring more particularly to Fig. 3, 25 and 26 are a power controlling cylinder and piston mounted on the locomotive and adapted to turn off the power by actuating the means, whether throttle or controller, which turn the power on and off. 27 is an air line provided on the intake side of the piston 26, and it is provided with a power controlling hand closed valve 28. 29 and 30 are a brake controlling piston and cylinder adapted to apply the brakes and having an air line 31 provided with a brake control hand closed valve 32. 33 are pneumatic means responsive to all the trips in set position, and it includes an impulse plunger 34 adapted to open and leave open the air control hand valve 38 at every impulse, and to normally close the brake control hand valve 32. As shown this pneumatic means includes a spring positioned pivotal lever 35 suitably mounted upon the locomotive or train and adapted to be turned in two directions by traveling over a set trip. The head of the lever 35 operates upon a valve stem 36 and causes it, when the lever is turned, to admit air by 37 to the cylinder 38 of the plunger 34, thus imparting an impulse to the spring retracted plunger 34. 39 is a pneumatic connection interposed in the out-

let side of the air line of the power controlling cylinder 25, and it includes a connector 40, adapted to connect the impulse plunger with the stem 41, of the air control and valve 32. At each impulse of the plunger 34, it operates the stem 42 to open the valve 28 and leave it open, and when the connector 40 is projected, the plunger 34 operates upon the stem 41, as has been said. Of course if the connector 40 is not projected or in projected position the plunger 34 does not reach the stem 41. The exact operation is that the first impulse or upward movement of 34 moves 42 and then 34 drops back. The movement of 42 shifts 26 to the left letting air past valve 28, opened by the upward movement of 42 and left open, and this air reaching 39 shifts 40 to the right, so that at the next upward stroke of 34, 32 is opened admitting air for the brake mechanism by way of 31. Inasmuch as at the second stroke of 34 the valve 28 is already open, the movement of 42 is an idle movement. If the signal is clear the projection 12 is clear of the circuit closers 13 and 14, so that the circuits are interrupted and the trips are retracted out of the path of the lever 35, so that the train control mechanism is inactive. If the signal is set at caution and if by inadvertence, accident and mistake the engine driver fails to observe it, the projection 12 has closed the circuit closer 13, as shown in Fig. 2, making circuit by way of 15, 13, 17, 20, 21, 6, 22 and 23, setting trip 1. As the train proceeds 1 trips 35 imparting an impulse to 34 which opens 28 and leaves it open causing 26 to shut off the power. This notifies the engineer that he has run by a caution signal and permits the train to drift. If, however, the signal had been set to stop, trips 1 and 2 would both have been set by way of 16, 15, the circuit then branching, one branch proceeding by 18, 21, 6, 22 and 23, and the other branch proceeding by 19, 24, 6 of trip 2, 22 and 23. In case the signal had been set at stop the power would be turned off as above described, but the connector 40 would be in position at the next impulse of 34 to permit it to open and leave open the valve 32 which controls application of the brakes, thus bringing the train to a full stop. By way of further description and not limitation, when the power goes off the engineer may permit sufficient time to lapse for the train to drift by the trip 2, and if it does that without setting the brakes, he can manually close the valve 28, which puts the automatic control out of action and operate his train in the usual way with regard to a caution signal, but if the second trip is set the brakes will be automatically applied as described and the train brought to a dead stop after which it will be necessary for the engineer to close the valves 28 and 32 manually and to then op-

erate his train in the usual manner, having of course ascertained from the signal that the line is clear.

It will be obvious to those skilled in the art to which the invention relates that modifications may be made in details of construction and arrangement and in matters of mere form without departing from the spirit of the invention which is not limited to such matters or otherwise than the prior art and the appended claims may require.

I claim:

1. Automatic train control apparatus including spaced electromagnetic trips, a signal interposed between the trips and having caution and stop positions, circuit connections between said trips and signal whereby at caution position the trip on the oncoming side is set and at stop position both trips are set, a power controlling piston and cylinder adapted to turn off the power and having an air line provided on the intake side with a power controlling hand closed valve, a brake controlling piston and cylinder adapted to apply the brakes and having an air line provided with a brake control hand closed valve, pneumatic means responsive to all trips in set position and including an impulse plunger adapted at every impulse to open and leave open the power control hand valve and to normally clear the brake control hand valve, and pneumatic connections interposed in the outlet side of the air line of the power controlling cylinder and adapted to connect the impulse plunger with the brake control valve to open and leave open the latter after the power controlling cylinder has completed a stroke and shut off the power.

2. In automatic train control apparatus an impulse device responsive to signals, a power control adapted to be actuated into shut off power position by one impulse of said device, a brake control adapted to be normally inactive in respect to said impulse device, and means arranged to receive air from the power control and responsive to the actuation of the power control into shut off power position and adapted to connect the brake control and impulse device to permit the latter upon repetition of an impulse to actuate the brake control to brake setting position.

3. Automatic train control apparatus comprising spaced electromagnetic track trips, a centrally positioned lever operative in two directions by the track trips, a pneumatic impulse plunger controlled by said lever, a pneumatic power control adapted to be actuated into shut off power position by one impulse of said plunger, a pneumatic brake control adapted to be normally inactive in respect to said plunger, and pneumatic means arranged to receive air from and controlled by the power means and adapted to

connect the plunger and brake control upon a repetition of the impulse of the plunger.

4. In automatic train control apparatus a centrally positioned lever operative in two directions, a pneumatic power control and a pneumatic brake control interconnected for the passage of air and adapted for opera-

tion in the order named, and a pneumatic plunger controlled by said lever and adapted to operate the power control on one ¹⁰ stroke and the brake control on a succeeding stroke.

MICHAEL SWORASKI.
